UNITED STATES PATENT OFFICE

143,684

DESIGN FOR AN ELECTRIC HEATER

Mont V. Van Fleet, Glendale, Calif.

Application April 4, 1945, Serial No. 118,851

Term of patent 14 years

(Cl. D81—10)

To all whom it may concern:

Be it known that I, Mont V. Van Fleet, a citizen of the United States, residing at Glendale, in the county of Los Angeles and State of California, have invented a new, original, and ornamental Design for an Electric Heater, of which the following is a specification, reference being had to the accompanying drawing, forming part thereof.

Figure 1 is an elevational view of an electric heater showing my new design.

Figure 2 is a plan view.

I claim:

The ornamental design for an electric heater, as shown.

MONT V. VAN FLEET.
